US00D965369S

(12) **United States Design Patent** (10) Patent No.: **US D965,369 S**
Gallagher (45) Date of Patent: **** Oct. 4, 2022**

(54) **BEVERAGE MAKING MACHINE
COMBINED WITH A SUNRISE ALARM
CLOCK**

(71) Applicant: **Helt Vildt Limited**, London (GB)

(72) Inventor: **Joe Gallagher**, London (GB)

(**) Term: **15 Years**

(21) Appl. No.: **35/512,452**

(22) Filed: **Jun. 30, 2021**

(80) **Hague Agreement Data**

Int. Filing Date: **Jun. 30, 2021**

Int. Reg. No.: **DM/215890**

Int. Reg. Date: **Jun. 30, 2021**

Int. Reg. Pub. Date: **Aug. 27, 2021**

(51) **LOC (13) Cl. 07-01**

(52) **U.S. Cl.**

USPC **D7/311**

(58) **Field of Classification Search**
